DEVICE FOR COLLECTING THE BLOOD AT
A CERTAIN PART OF THE HUMAN BODY

Bruno Höflinger, Berlin, Germany

Application June 5, 1935, Serial No. 25,161
In Germany February 26, 1935

5 Claims. (Cl. 128—327)

This invention relates to a device for collecting the blood at a certain part of the human body, wherein the pressure medium produces a constriction zone which progresses through the device to the point where it is desired to collect the blood. In such a device, in accordance with this invention, the pressure medium is admitted into the device, preferably into the first chamber thereof if the apparatus comprises a plurality of chambers disposed one beside the other, so that the pressure medium enters these chambers one after the other in succession and in such a way that the admission does not cause inconvenience even if the person using the device performs bodily movement during the use thereof. With this object in view, in the blood collecting device according to the invention the first annular chamber to be filled with fluid under pressure is provided with a small non-return valve, which is so constructed that the end of a hose attached to a rubber bulb supplying the fluid under pressure can be quickly and easily detached from the valve after having supplied the fluid under pressure.

The invention will now be more particularly described with reference to the accompanying drawing which illustrates several embodiments of the invention by way of example, and wherein:

30 Fig. 1 shows the arrangement of the pressure chambers.

Fig. 2 illustrates a fragmentary part of Fig. 1 on a larger scale.

Fig. 3 shows a valve according to the invention, wherein the axis of the valve is perpendicular to the surface of the cylinder of the device.

Fig. 4 shows a second embodiment, wherein the axis of the valve is tangential to said surface, and Figs. 5 and 6 show two modifications of the valve member.

Referring to Fig. 1, pressure is established in the lowermost chamber 2 by means of the air admission device *f*. The excess of fluid under pressure then passes through the short tubular connecting member *f10* from the pressure chamber 2 into the adjacent pressure chamber 2c and from this chamber through the tubular connecting member *f11* to the next adjacent pressure chamber 2d.

50 In this manner pressure may be established in any desired number of pressure chambers, one after the other. In this connection it is, of course, necessary that the fluid under pressure shall not be able to pass from one chamber to the other without control, but that it shall be restricted

in its passage by suitable resistances. Such resistance may, for example, be provided by introducing into the short connecting tubes *f10* and *f11* small inserts *f13* (Fig. 2) provided with jet like passages *f14* which are very fine, their diameters being only a fraction of a millimetre. By suitably selecting these constrictions the result may be obtained that the fluid under pressure will pass to the second chamber only after having filled the first chamber, and so forth.

10 The blood collecting apparatus according to the invention includes a comparatively un-stretchable casing 1 made of fabric reinforced rubber or the like. Disposed on the inner side of this casing there are a series of flat annular chambers 2, 2c, 2d, which are made of highly elastic material and are adapted to be filled with fluid under pressure. The chamber 2 is first filled with fluid under pressure, and as shown in the drawing has an opening in its wall in 20 which is mounted the valve *f*. This valve comprises a valve body 3 slidably mounted in guides in the valve casing 4 sufficient clearance between the body and the walls of the casing being provided to permit passage of the fluid around the 25 valve's periphery. The casing 4 is closed at its outer end by a member 5 which is secured thereto by means such as screw threads. The valve body has a guide pin 6 at its inner end and a 30 guide pin 7 at its outer end. The guide pin 7 passes through a bore in the member 5 and has sufficient play therein to permit passage of the fluid, while the guide pin 6 passes through a bore in the inner end of the valve casing 4 and has sufficient play to permit passage of the fluid. 35 A pumping bulb 8 is attached to be slipped over the member 5.

In Fig. 3 the casing 1 and the wall of the chamber 2 are compressed between a flange in the inner end of the casing 4 and the member 5 so 40 that when the member 5 is screwed on member 4 the valve *f* will be secured in position thereby, assisted by the annular projections and grooves 9 and 10 provided on the members 4 and 5.

The valve construction may be altered in such 45 a way that the valve body 3 makes a sliding fit in the casing 4 and is provided with axial grooves which enable the inflow and outflow of the air in the open position of the valve.

The member 5 is about 2 cm. long and its side 50 walls are concave to suit the corresponding convex portion of the tubular extension of the pumping bulb 8, which may be attached thereby in an air tight manner to the valve closing member and yet may be easily detached therefrom.

The end of the member 5 is also concave, and the valve pin 7 extends into this concavity. The latter substantially conforms with the tip of a thumb, which may enter the concavity when it is desired to depress the pin 7. The end of the valve body 3 adjacent the member 5 is provided with an annular rubber gasket 11, which is adapted to firmly engage in an air tight manner an annular boss 12 of the member 5 when pressure is exerted upon the rear end of the valve body, so that the fluid under pressure in the annular chambers 2, 2c, 2d cannot escape after the removal of the pumping bulb 8. The annular boss 12 has a sharp edge which penetrates deeply into the soft rubber gasket 11 as soon as the pressure at the inner side of the valve body rises above the atmospheric pressure.

When it is desired to remove the fluid under pressure from the annular chambers 2, 2c, 2d, a slight pressure is exerted upon the valve pin 7, so that the air within the chambers, which is at a pressure higher than atmospheric air, may escape between the rubber gasket 11 and the annular boss 12.

In the embodiment shown in Fig. 4 a coil spring 13 acts upon the inner end of the valve body 3. Such a spring may also be provided in the embodiment shown in Fig. 3, but it is not essential. In Fig. 4 the air passage tube 14 leading to the chambers 2, 2c, 2d is disposed below the valve body 3. In this embodiment the packing is effected by providing in the outer end of the valve body an annular recess in which is disposed a rubber gasket 15 which may be pressed against an annular projection 16 on the member 5. In addition, an annular rubber gasket 17 may be provided on the rear end of the closing member 5, for engagement with the outer end of the valve body 3 when pressure higher than atmospheric is exerted upon the rear end of the valve body, this pressure being assisted by the action of the spring 13. The removal of the fluid under pressure from the annular chambers is effected in this embodiment also by exerting a slight pressure upon the valve pin 7. It should be noted that it is preferable to dispose the valve casing 4 in this embodiment substantially tangent to the wall 1, this affording better protection against same being torn off the cylinder casing.

As it is important, that the rubber gaskets make a tight joint when the valve is seated, even under slight air pressures and it may be desirable according to the invention to use (instead of the solid rubber gasket 11 of Fig. 3) a chamber 11a (Fig. 5) in the outer end of the valve body 3 and to close this chamber by a thin rubber diaphragm 11b, which will make a tighter joint with the annular boss 12. The chamber 11a may also be subjected to a small fluid pressure, especially air pressure, which could be effected as shown in Fig. 6 by providing ducts 5b and 5c, through the pin 7 communicating

with the chamber 11a. The axially disposed bore 5b is closed by a little rubber cap 11c. The latter may consist of a thin rubber diaphragm which closes the bore 5b in an air tight manner after establishing the pressure in the chamber 11a, at which time the actual surface of the diaphragm 11b is somewhat arcuate as shown in Fig. 6, so that the joint between the diaphragm and boss 12 will be better effected. The diaphragm 11b acts in this modification like an air cushion.

I claim:

1. In a device for collecting the blood at a certain part of the human body, a plurality of inflatable chambers connected in series and forming a tube open at its ends; resistances in the connections between the chambers for regulating the flow of pressure medium from chamber to chamber, said resistances increasing successively in value to offer increased resistance to the pressure medium in passing from chamber to chamber; a hollow stem extending from the end chamber whose connection has the lowest value resistance; a check valve in said stem; means for unseating the check valve to permit escape of pressure medium from the chamber; and pressure generating means detachably connected with the stem.

2. In a device for collecting the blood at a certain part of the human body, a substantially non-expandable tubular casing open at its ends; a plurality of annular inflatable chambers connected in series within the casing; resistances in the connections between the chambers for regulating the flow of pressure medium from chamber to chamber in a direction towards the point where the blood is to be collected; said resistances increasing successively in value to offer increased resistance to the pressure medium in passing from chamber to chamber; a hollow stem extending from the end chamber most remote from the blood collecting point; a check valve in said stem; means for unseating the check valve to permit escape of pressure medium from the chamber; and an elastic pumping bulb for supplying fluid under pressure detachably connected with the stem.

3. In a device as set forth in claim 2, the outer wall of the stem being concave and adapted to enter the stretched end of the bulb to maintain the bulb on the stem.

4. In a device as set forth in claim 2, said means comprising a member on the valve extending through the stem and adapted to be manually shifted.

5. In a device as set forth in claim 2, said stem having a shallow recess in one wall; and said means comprising a pin on the valve extending through the stem and terminating within the recess and adapted to be engaged by a person's finger.

BRUNO HÖFLINGER.
